UNITED STATES PATENT OFFICE.

RUDOLPH KNOOPP AND JOSEPH G. BIEHLER, OF ROCHESTER, NEW YORK, ASSIGNEES OF
ONE-FIFTH TO FRANK KEIPER.

LABELING-MACHINE.

1,299,194.

Specification of Letters Patent.

Patented Apr. 1, 1919.

Application filed December 10, 1913. Serial No. 805,745.

To all whom it may concern:

Be it known that we, RUDOLPH KNOOPP and JOSEPH G. BIEHLER, a subject of the Emperor of Austria, and a citizen of the 5 United States, respectively, residing at Rochester, in the county of Monroe and State of New York, have invented certain new and useful Improvements in Labeling-Machines, of which the following is a specification.

The object of this invention is to provide a new and improved machine for applying labels to boxes, more especially for applying revenue stamps to cigarette boxes.

15 Another object of the invention is to provide a new and improved selecting and feeding mechanism for taking the labels from a magazine and applying them to the package.

20 Another object is to provide an improved device for applying paste to the label.

Another object is to provide an improved conveyer for feeding the packages through the machine.

25 Another object of the invention is to provide an improved device for causing the labels to adhere to the packages.

In the accompanying drawings, Figure 1 is a top plan view of the machine.

30 Fig. 2 is a section on the line 2^x—2^x of Fig. 1 of the machine, showing the driving mechanism of the machine.

35 Fig. 3 is a detail view of the cam movement for operating the label pick-up-mechanism.

Fig. 4 is a vertical section on the line 4^x—4^x of Fig. 1.

Fig. 5 is a perspective view of a part of the label selecting mechanism.

40 Fig. 6 is a detail view of the hopper for holding the labels and a portion of the selecting mechanism, the figure being taken on the line 6^x—6^x of Fig. 5.

Fig. 7 is a detail view of the parts shown in Fig. 6 showing them in a different position.

Fig. 8 is a detail view of the feeding mechanism for the packages.

Fig. 9 is a vertical section on the line 9^x—9^x of Fig. 4.

Fig. 10 is a vertical section on the line 10^x—10^x of Fig. 4.

Figs. 11 and 12 are detail views of a por-

tion of the mechanism for feeding the labels in the reservoir.

Fig. 13 is a horizontal section on the line 13^x—13^x of Fig. 4.

Fig. 14 is a perspective view of the guides for holding the selected label in upright position.

Fig. 15 is a perspective view of the end of the hopper for holding the labels and the roller for feeding them.

In the accompanying drawings, like reference numerals refer to like parts.

Reference numeral 1 indicates the frame of the machine, which frame consists of the end pieces 2 and 3 which are connected together by the side bars 4 and 5. These side bars are connected at suitable intervals by the cross bars 23^c, 23^d, 90, 91, 92 and 93, 95, 96. Short brackets 94 are used for supporting the bars 22 and 22^a from the sides without interfering with the travel of the chain.

The ends 2 and 3 each have integral therewith the legs 6 and 7 shown in Figs. 4 and 9.

Mounted on the bars 4 and 5 are bearings for various shafts as follows:

The bearing block 8 for the shaft 9 and the bearing block 10 for the shaft 11. Similar bearing blocks are provided on the opposite side of the machine for both of these shafts. The bearing block 12 is provided in which is supported the main power shaft 13 and the shaft 14. On the main power shaft 13 is provided the pinion 15 which meshes with the idler pinion 16 mounted on the shaft 14 which idler pinion meshes with the pinion 17 on the shaft 11. The shaft 14 is a short shaft which does not extend clear across the machine but the shafts 9, 11 and 13 do extend clear across the machine and for them similar bearings are provided in the opposite side of the machine.

Mounted on the shafts 9 and 11 are the sprocket wheels 18 and 19 on which are mounted to travel the chains 20. It will be understood that there are two of the chains 20 as is shown in Fig. 8 and the sprocket wheels 18 and 19 are provided in pairs accordingly on their respective shafts. Mounted on the frame of the machine is the hopper 21 in which are contained the cigarette boxes or other packages on which the revenue stamps or labels are to be affixed. The chain 20 travels across the bottom of

this hopper and operates to take the cigarette packages one at a time as follows:

Between the hopper and the chain is provided the guides 22 and 22^a upon which the 5 bottom package in the hopper rests. The chain 20 is adapted to travel under the open space between the guides 22 and 22^a. (See Fig. 9). To the right of the hopper are also provided the guides 23 and 23^a and the cigarette boxes, as they travel from the hopper 10 to the right, in Fig. 4, pass between the lower guides 22 and 22^a and the upper guides 23 and 23^a.

Between the sprocket wheels and the chain 15 is provided the stationary guide 24 supported by the cross bars 95 and 96. Mounted between the chains are the blocks 25 having the lugs 26 thereon between which are pivotally mounted the swinging pusher 20 plates 27 which plates are angular in cross section and are illustrated in perspective in Fig. 8. As is shown in Fig. 8, they have the 25 upright member 27^a or head and the horizontal member or tail 27^b. The horizontal member 27^b is intended to slide along and make contact with the bar 24, (see Figs. 1, 4 and 9), holding the member 27^a firmly in an upright position as it travels under the 30 hopper so that it can properly push the bottom package along between the guides 22, 22^a, 23 and 23^a from the hopper to the labeling mechanism. The pushers 27 are held in the position shown in Fig. 8 when traveling forward by the bar 24 which keeps them 35 from falling back and by the shoulders 27^c which make contact with the lugs 26 which prevent them from falling forward. The bar 24 ends so as to leave the pusher 27 free to swing back when the box has been pushed 40 just beyond the rollers 80 and 81.

Each of the sprocket wheels 18 and 19 is provided with seven teeth and the chain 20 is provided with links that are any suitable multiple of this number, preferably as is 45 shown in the drawings of twenty-eight links, the chain also being provided with four pusher plates, the ratio of the gearing being such that the chain will feed one box for each revolution of the shaft 11 and for 50 each revolution of the shaft 13. The pusher plates are spaced apart on the chain considerably more than the length of the box for the purpose of bringing the boxes intermittently to the labeling mechanism. That 55 is, with an interval between the boxes as they are fed to the labeling mechanism.

Mounted on the frame of the machine is the hopper 30 in which is contained the labels 31 or the revenue stamps that are to 60 be affixed to the packages. In the sides of this hopper are formed the grooves 32. In the hopper, the traveler 33 is adapted to move. This traveler has a pin 34 extending through it which engages with the grooves 65 32 in the sides of the hopper. Fastened to

the pin 34 are the strings 35 which pass around the idle pulley 36 at the front of the hopper and around the winding drums 37 at the rear of the hopper which drums are integrally connected by a sleeve, which 70 sleeve is in turn mounted on the shaft 38 on which it is adapted to turn. The spring 39 is provided one end of which is connected to the shaft 38 and the other end of which is connected to the pin 40. For the purpose of connecting the shaft 38 to the drums 37 so that the drums can be rotated by the spring 39, I provide the ratchet wheel 41 which is keyed to the shaft and the pawl 42 which is pivotally mounted on one of the 80 drums 37. By this arrangement it is possible to turn the shaft 38 winding up the spring 39 to any desired tension without moving the drums 37 thus regulating the tension on the cords 35 by which the traveler 33 is driven. At the open or forward end of the hopper are formed the flanges 130 and 131, which flanges are bent up on the sides of the magazine between which flanges is a slot in which works the pad 72 90 on the feed roller 71. These flanges extend only part way up on the reservoir, they being left short so that the end of the label contained in the reservoir will be exposed 95 above them.

At the open end of the magazine 30 a selecting mechanism is provided for the purpose of transferring the labels or revenue stamps, one at a time from the magazine and applying them to the boxes and this 100 selecting mechanism will now be described as follows:

Mounted on the frame of the machine is the stud 45 on which is mounted the idle gear 46. Mounted on the frame of the machine is the bearing block 47 in which is mounted the shaft 48 having the pinion 49 thereon. Also mounted in the bearing block is the shaft 50 having the pinion 51 thereon. The shaft 50 extends through the 110 machine and has the pinion 52 thereon, (see Fig. 1), which pinion meshes with the pinion 53 mounted on the shaft 54. The shaft 54 also carries the cam plate 55 having the cam 56 cut therein. On the bearing block is 115 also mounted the shaft 57 on which is mounted the segmental internal gear 58 which meshes with the pinion 59, mounted on the shaft 60. The cam 55 rotates continuously with the shaft 54 and will communicate an oscillating motion to the shafts 57 and 60.

On the shaft 57 is provided the sucker 61 which is hollow as shown at 62 and has openings 63 in the face thereof as is shown in 125 Figs. 5, 6 and 7. A crank is formed at each end of the sucker integral therewith. The crank at one end is used to support the sucker on the shaft 57 and the crank at the other end is hollow as shown in Fig. 5 and 130

the tube 64 is attached thereto which tube communicates with the opening 65 in the suction pump 66 which suction pump has a piston 67 therein which is driven in one direction by the eccentric 68 on the shaft 13 and is driven in the other direction by the compression spring 69. The parts are so timed that the pump will cause a suction in the sucker 61 when the sucker 61 is rotated to the position shown in Fig. 7 which suction is maintained as the sucker rocks toward the position shown in Fig. 6.

When the sucker is in the position shown in Fig. 7, the suction will cause the first label to adhere thereto and will bend it to the position shown in Fig. 6, the remaining labels retaining their normal position.

Coöperating with this sucker is the retaining device 70 carried on the shaft 60 which rocks to press against the labels in the magazine 30 and grip them after the suction device has pulled away the first label and holds them until the feed roller 71 has pulled down the label selected by the sucker. The selected label is fed down and pasted as follows:

Mounted on the shaft 54 is the feed roller 71 having the rubber pad 72 thereon. This rubber pad is adapted to make contact with and draw down the outer label, that is the one that has been bent out at the top by the suction device. This rubber pad 72 is about three-fourths of the length of the label to be fed thereby. As the roller 71 and its pad 72 rotates, the edge of the pad 72 makes contact with the label substantially on the line horizontal with the shaft 54, on which the roller is mounted and draws the label down, feeding the label to the paste roll 73 mounted on the shaft 48. Opposite the paste roll is provided the feeding roller 74 between which and the paste roll 73, the label is carried down. Both the paste roll 73 and the feed roller 74 have annular grooves centrally thereof as is shown in Figs. 10 and 13. Extending through these annular grooves to the feed roll 71 is provided the vertical stationary guides 75 (see Figs. 4, 13 and 14), between which the label is guided as it moves downwardly from the magazine to the package. The label is also held against edgewise movement by the guides 75^a and 75^b. (See Fig. 14). The paste roll 73 has a raised segmental surface that is slightly shorter than the length of the label. Paste is applied to this raised segmental surface by the paste roller 76 to which paste is fed by the roller 77 which runs in a reservoir of paste 78. The peripheral velocity of the roller 73 is greater than the peripheral velocity of the roller 76 and the roller 76 in turn has a greater peripheral velocity than the roller 77 and the gearing is arranged to secure this result. This is for the purpose of securing better

transfer of the paste from one roller to the next.

The rollers 73 and 74 feed the label down until it strikes the pocket 79 by which it is held in position so that it stands across the path of movement of the package. As the package is carried forward by the chain 20 heretofore described, the end of the package engages with the middle of the label and carries the label forward with it. The rollers 80 and 81 (see Fig. 4), are provided between which the package must pass, which rollers serve to double the label over the package and press it down on the package. The pushers 27 carry the packages forward beyond the guides 75 and pocket 79, (see Fig. 4), so as to leave the space open for the next label as it is fed down. The next package as it is fed along, picks up this label and carries it forward, pushing the preceding package ahead of it and in this manner, the packages are fed successively through the machine and the labels are affixed thereto. The upper bar 22 as shown in Fig. 1, extends continuously from one end of the machine to the other while the lower bar 22^a, extends as is shown in Fig. 4, being interrupted by the roller 80 and terminating short of the end of the machine to permit the packages to drop through into the delivery chute 86.

The bar 23 extends from the cross bar 23^c to the cross bar 23^d and the bar 23^a extends from the cross bar 23^c to the roller 81. In line with the bar 23^c is provided the flat spring 82 which spring is fastened at one end to the bearing block that carries the roller 81 which bearing block is held in place by the pin 83. The spring 82 extends rearwardly and is pressed down at suitable intervals by means of fingers 84 carried in the housing 85 in which they are pressed downwardly by suitable coiled springs. The downward pressure of the springs in the housings 85 may be varied by turning the housings. This spring 82 causes a moderate pressure to be exerted on the label pressing it down so that it will firmly adhere to the package which pressure is exerted on the label as it travels to the delivery chute 86. On the cross bar 23^d the spring finger 87 is provided which presses the boxes down as they advance so they fall into the delivery chute 86.

The housings 85 are supported on the cross bars 23^d, 92 and 93.

Cross bars 100, 101 and 102 are provided to support the bars 22 and 22^a, and the cross bar 103 is provided to support the air pump 66. From the cross bar 103 extends a bracket 104, see Fig. 1, from which is supported the two pivots 105 and 106 on which are supported for swinging movement the arms 107 and 108. These arms are connected so as to swing together and the arm 108

- 108 carries the pin 109 which engages with the cam 110 carried on the shaft 13 by which an oscillating movement is given to the arms 107 and 108. At the rear end these bars 5 carry a pusher plate 111 by which the packages are pushed out of the machine as they drop into the delivery chute. Flat springs 112 and 113 are provided in the chute for holding the packages in an upright position.
- 10 In using labels of different lengths it is desirable to adjust the hopper 30 at the front end so that the top of the labels will always come into contact with the sucker. For this purpose the cross bar 114 is provided in connection with the bearing block 47. In this bearing block, work the adjusting screws 115 and 116, which support the cross bar 117 fastened to the front of the hopper. On this bar 117 are the locking 15 screws 118 and 119 by which the bar 117 may be locked in place when it has been adjusted. A driving pulley 120 is loosely mounted on the main shaft 13 and a clutch 121 is provided on the shaft for coupling 20 the pulley to the shaft.
- 25 We claim:

1. In a machine the combination of a hopper for labels, a sucker for selecting the end label in said hopper, means for clamping the balance of the labels in said hopper and means for feeding the selected label, and means for applying paste thereto, said sucker and clamping means operating on one end of the label and the feeding means 30 operating on the other end of the label, said clamping means oscillating on a single fixed axis, having its bearing outside of and at one side of the magazine.

2. In a machine the combination of a hopper for labels, a sucker for selecting the end label in said hopper, means for clamping the balance of the labels in said hopper, means for feeding the selected label, means for applying paste thereto, and means for feeding a package into contact with said 45 label, said clamping means oscillating on a single fixed axis, having its bearing outside of and at one side of the magazine.

3. In a machine the combination of a hopper for labels, flanges at the end of said hopper to hold the labels therein, a slit at the bottom of the flanges through which the labels can pass down from the hopper, a roller working between said flanges and 50 making contact with the end label in the hopper to feed it down to said slit, and means for clamping all but the end label in the hopper.

4. In a machine the combination of a hopper for labels, flanges at the end of said hopper to hold the labels therein, a slit at the bottom of the flanges through which the labels can pass down from the hopper, a 55 roller segment working between said flanges and making contact with the end label in

the hopper to feed it down to said slit, means for clamping all but the end label in the hopper, and a sucker for selecting the end label and holding it free from said clamping means.

70

5. In a machine the combination of a hopper for labels, flanges at the end of said hopper to hold the labels therein, the bottom of the hopper being cut away at the flanges to form an opening through which the labels can pass down from the hopper, a sucker oscillating above said flanges to make contact with the end label in said hopper and draw it out away from the remaining labels in said hopper and means for feeding said label from the hopper.

6. In a machine the combination of a hopper for labels, flanges at the end of said hopper to hold the labels therein, the bottom of the hopper being cut away at the flanges to form an opening through which the labels can pass down from the hopper, a sucker oscillating above said flanges to make contact with the end label in said hopper and draw it out away from the remaining labels in said hopper means for intermittently producing suction in said sucker and means for feeding said label from the hopper.

85

7. In a machine the combination of a hopper for the labels, means for feeding the end label from the hopper, means for holding the remaining labels in the hopper, a guide through which the end label passes from the hopper, means for putting paste on the label 100 as it passes through said guide, and a pocket below said guide into which the label is fed from said guide.

95

8. In a machine the combination of a hopper in which the labels are adapted to stand vertically, flanges at the end of the hopper to hold the labels therein, said flanges being shorter than the labels, a sucker operating above said flanges to select the end label in the hopper, means for clamping the remaining labels in the hopper, and means for operating on the other end of the label to feed it from the hopper.

105

9. In the machine, the combination of a hopper, a feeding device for feeding from said hopper, comprising a continuously rotating cam, an internal segmental gear rocked by said cam, a pinion driven by said internal segmental gear, a sucker rocked with said segmental gear and a clamping device 115 rocked with said pinion.

110

10. In a machine the combination of a horizontal guide for feeding packages, means for feeding a label at right angles to and across said horizontal guide, means for applying paste to the label before it travels across said horizontal guide, a pocket into which the label is allowed to drop and in which it is held stationary across said horizontal guide, means for feeding packages 125

120

125

130

- along said horizontal guide to engage the label near its center, and means for folding said labels over the package as it is fed along said horizontal guide.
- 5 11. In a machine the combination of a frame, a chute therein through which packages are adapted to pass, a spring blade on one side of said chute adapted to exert yielding pressure upon the packages, means 70 mounted at intervals on said frame for applying the yielding pressure on said spring, and means for forcing the packages along said chute.
12. In a machine the combination of a 15 pair of feed rollers, each of said rollers having an annular groove therein, centrally thereof, means for applying paste to one of said rollers, a pair of straight stationary guide bars extending between said rollers in 20 the grooves thereof, stationary guides on both sides of said rollers, and a pocket below said rollers for holding the label after it has been fed by said rollers.
13. In a machine the combination of a 25 hopper, a conveyer traveling across the bottom of said hopper and adapted to feed packages at regular intervals from said hopper along the machine, a hopper for labels having the end thereof located above the 30 end of the conveyer, means for selecting and feeding labels at regular intervals from the end of said hopper and moving them toward the end of said conveyer, means for coating said labels with paste and means for affixing 35 the coated labels to said packages.
14. In a machine the combination of means for feeding packages at regular intervals, a hopper for labels, means for selecting and feeding labels at regular intervals from 40 the end of said hopper, said means including a sucker for selecting the end label in said hopper, means for clamping the balance of the labels in said hopper and means for feeding the end label from the hopper, means for 45 coating the selected label with paste, and means for affixing the coated labels to said packages, said clamping means oscillating on a single fixed axis, having its bearing outside of and at one side of the magazine.
- 50 15. In a machine the combination of means for feeding packages at regular intervals, a magazine for labels, means for selecting and feeding labels at regular intervals from the lower end of said magazine, 55 said means operating to feed the labels at right angles to the path of movement of the packages, and means for thereafter coating said labels with paste and placing said labels across the path of movement of the packages, the movement of each package operating to double the label therefor over the package and carrying it with the package, causing the label to adhere 60 to the package, clamping means for preventing the feed of all but the end label from the hopper, said clamp- 65 ing means oscillating on a single fixed axis, having its bearing outside of and at one side of the magazine.
16. In a machine the combination of means for feeding packages at regular intervals, a magazine for labels, means for selecting and feeding labels at regular intervals from the lower end of said magazine, and means for thereafter coating said labels with paste and placing said labels across the path of movement of the packages, the movement of each package operating to double the label therefor over the package and carry it with the package and cause the label to adhere 70 thereto.
17. In a machine the combination of a conveyer having pushers thereon, said pushers being adapted to engage with packages and push them along with the conveyer, at regular intervals, a magazine for labels, means 75 for selecting and feeding labels at regular intervals from the lower end of said magazine into the path of said packages, and means for thereafter coating said labels during the feeding thereof, the movement of each package operating to double the label therefor over the package and carry it with the package, causing the label to adhere 80 thereto.
18. In a machine the combination of means 85 for feeding packages at regular intervals, a hopper for labels, flanges at the end of said hopper to hold the labels therein, a slit at the bottom of the flanges through which the labels can pass down from the hopper, a 90 roller working between said flanges and making contact with the end label in the hopper to feed it down to said slit, means for clamping all but the end label in the hopper, a sucker for selecting the end label and holding it free from said clamping means, and means for coating said labels with paste and placing said labels across the path of movement of the packages, the movement of each package operating to double the label therefor over the package and carry it with the package and cause the label to adhere 95 thereto.
19. In a machine the combination of a 100 hopper, means for feeding packages from said hopper, said means comprising a pair of guides, a conveyer working between said guides, said conveyer having dogs pivotally mounted thereon, shoulders on said dogs which prevent said dogs from swinging forward, tails on said dogs, a guide mounted adjacent to said conveyer with which said tails make contact to prevent the dogs from swinging backward, said dogs being capable of swinging backward after 105 they pass the end of the guide, means for selecting and feeding labels at regular intervals, and means for coating said labels with paste and placing said labels across the path of movement of the packages, the movement 110
- 120
- 125
- 130

of each package operating to double the label therefor over the package and carry it with the package and cause the label to adhere thereto.

5 20. In a machine the combination of a hopper for labels, a sucker for selecting the end label in said hopper, means for clamping the balance of the labels in said hopper, said sucker and clamping means operating 10 on the rear end of the label, a roller located at the forward end of the label operating to feed the selected label, said roller having a raised segment that makes contact with the end label to feed it, said clamping means 15 oscillating on a single fixed axis, having its bearing outside of and at one side of the magazine.

21. In a machine the combination of a hopper for labels, a sucker for selecting the 20 end label in said hopper, means for clamping the balance of the labels in said hopper, said sucker and clamping means operating on the rear end of the label, a roller located at the forward end of the label operating to 25 feed the selected label, said roller operating to turn continuously but making contact with the end label intermittently, said clamping means oscillating on a single fixed axis, having its bearing outside of and at one side 30 of the magazine.

22. In a machine the combination of a hopper having a short vertical flange on each side thereof at the end thereof with an open space between and above said flanges, a 35 roller operating between said flanges to feed the end label downward, a sucker and clamping device working on the end label in the open space above said flanges to select and separate the top of the label from the remaining labels in the hopper.

23. In a machine the combination of a hopper having a short vertical flange on each side thereof at the end thereof with an open space between and above said flanges, a 45 roller operating between said flanges to feed the end label downward, said roller operating to turn continuously but making contact with the end label intermittently, a sucker and clamping device working on the 50 end label in the open space above said flanges to select and separate the top of the label from the remaining labels in the hopper.

24. In a machine the combination of a 55 hopper for labels, a sucker for selecting the end label in said hopper, means for clamping the balance of the labels in said hopper and means for feeding the selected label, and means for applying paste thereto, said 60 sucker and clamping means operating on one end of the label and the feeding means operating on the other end of the label, said clamping means oscillating on a single fixed axis, said clamp and said sucker each making contact with the end of the label at sub-

stantially the same place, the clamp being pivoted on one side of said place of contact and the sucker being pivoted on the other side of said place of contact.

25. In a machine the combination of a 70 hopper for labels, a sucker for selecting the end label in said hopper, means for clamping the balance of the labels in said hopper and means for feeding the selected label, and means for applying paste thereto, said 75 sucker and clamping means operating on one end of the label and the feeding means operating on the other end of the label, said clamping means oscillating on a single fixed axis, said clamp and said sucker each making contact with the end of the label at substantially the same place, the clamp being pivoted on one side of said place of contact and the sucker being pivoted on the other side of said place of contact, the 80 pivots of both being close to the plane of the label.

26. The combination of guides for packages adapted to hold said packages in line both from above and below, a conveyer 90 working between said guides, said guides extending beyond the conveyer, dogs pivotally mounted upon said conveyer adapted to push packages along said guides, said guides having an opening extending transversely 95 thereto in which opening a label can be placed across the path of movement of the packages, means to hold said dogs in position to push a package during a certain part of their travel, said dogs being permitted to swing backward after they have pushed the package along the guide beyond said opening.

27. In a machine the combination of a 105 hopper for labels, a sucker for selecting the end label in said hopper, means for clamping the balance of the labels in said hopper and means for feeding the selected label, said sucker and clamping means operating 110 on one end of the label and the feeding means operating on the other end of the label, said clamping means oscillating on a single fixed axis and having a radial clamping surface and having its bearing outside of and at one end of the magazine.

28. In a machine the combination of a 115 hopper for labels, a sucker for selecting the end label in said hopper, means for clamping the balance of the labels in said hopper, said clamping means oscillating on 120 a single fixed axis and having a radial clamping surface and having its bearing outside of and at one end of the magazine.

29. Labeling apparatus, comprising a 125 magazine label holder having provision for pressing the labels against one end thereof, the delivery end of the holder having lateral retaining means arranged to leave one side of the foremost label free, a picker device mounted for reciprocation to engage the 130

free side of the foremost label and bend it outward, a presser member connected to move into engagement with the rest of the label stack behind the bent out end of the 5 foremost label, a wiper member arranged to transfer the foremost label from the stack, and means for feeding boxes into position for application of the labels thereto.

30. Labeling apparatus, comprising a magazine label holder having provision for 10 pressing the labels against one end thereof, an oscillatory picker arranged to engage one side of the foremost label and bend it outward, an oscillatory presser beak in geared connection with said picker so as to

move into position to press upon the rest 15 of the label stack behind the foremost label, a wiper also in geared connection with said picker for transferring the labels from the stack, adhesive applying means, and box feeding means arranged to apply the labels 20 to the boxes, as the labels are delivered from said adhesive applying means.

In testimony whereof we affix our signatures in presence of two witnesses.

RUDOLPH KNOPP.

JOSEPH G. BIEHLER.
